JAMES A. McCRACKEN, OF LOS ANGELES, CALIFORNIA

METHOD OF AND APPARATUS FOR PRODUCTION OF FOAM SOLUTIONS

Application filed September 28, 1927. Serial No. 222,637.

My invention relates to the continuous production of solutions of the chemicals used to produce a fire extinguishing foam.

It relates more particularly to means by which, water under pressure being available in the neighborhood of a fire, foam may be continuously generated on the spot without the use of pumps or other energy producing devices, by introducing the foam chemicals into streams of water in such manner that these streams do not lose their energy but may be conducted by means of their original pressure to the point of intermixture and of foam production.

15 The manner of extinguishing fires with foam is well known and understood. It consists in applying to the burning surface or liquid a froth produced by intermixing solutions (a) aluminum sulfate (b) sodium b10 carbonate and a stabilizing agent such as licorice. On mixing these solutions carbon dioxide is set free, aluminum hydrate is precipitated in gelatinous form, and the licorice acting to increase the surface tension of the liquid, a very dense and permanent froth consisting substantially of water and having a high value for extinguishing fires is produced. This foam is flowed or sprayed over the surfaces of burning liquids, and is plastered over burning wood by ejection under pressure through a nozzle.

The chemicals above described are herein-after referred to as foam producing agents, or simply as agents, and when reference is made to an agent it will be understood that I refer to either the (a) or the (b) chemical above, while if the reference is to agents in the plural it will be understood that one of the agents referred to is the (a) chemical and the other the (b) chemical, by the combination of which the desired foam is produced.

45 In the system in most general use it has been the practice to prepare the two solutions in advance, store them until required for use, and conduct them to the seat of the fire through separate pipe lines under the pressure generated by pumps located near the storage tanks. The solution of aluminum sulfate is acid and corrosive to metal, and if

left standing in lines will put them out of commission. Both solutions depreciate somewhat on standing and must be checked and restandardized, and the pumps tested at frequent intervals.

As the solutions are bulky a large amount of storage (half of which must be lead lined) must be provided for the protection of a risk such as an oil refinery. In addition there must be a complete system of double pipe lines extending to all parts of the area to be protected. Attempts to mix the solutions near the storage plant and conduct the foam through a single line have not been successful, owing to the breaking down of the foam by friction in transit. The storage and pipe line system heretofore used, while in most cases quite efficient, has therefore proven extravagantly expensive to install and to keep in operating condition.

A type of portable extinguishers has heretofore been used, comprising tanks for the chemicals and pumps for forcing them to the point of intermixture, but such portable units, even when mounted on motor trucks, have had a very limited capacity, because of the great weight of water to be transported, the total solution consisting substantially of one part by weight of active chemical to eight parts by weight of water. Thus a portable unit having a net weight of ten tons (a very large size) would consist of about one ton machinery and tanks, eight tons water and one ton actual fire extinguishing material.

By the use of my present invention the entire standing system of storage tanks and pipe lines may be done away with and an unlimited quantity of foam produced, continuously, by the use of a portable unit weighing only a few hundred pounds. The only requisite is a supply of water under pressure in the general vicinity of the point at which the portable unit is to be spotted, such supply being usually already available.

My invention comprises a method and an apparatus by means of which the dry powdered chemicals can be separately brought into solution in flow streams of water, by means of the pressure on the water system.

and without the use of pumps or other machinery. A preferred application of said invention is diagrammatically illustrated in the attached drawings, in which

5 Figure 1 is a vertical section of the simplest form of my solution producing device.

Figure 2 is a plan section on the line A—A of Figure 1,

10 Figure 3 is a vertical section of a more refined design, adapted to make both solutions at the same time, and

Figure 4 is a plan section on the line B—B of Figure 3.

15 Referring to Figures 1 and 2, 1 is a cylinder having a tight head 2 into which is permanently fixed the water pipe 3, controlled by the valve 8 and communicating through a flexible connection with a supply of water under pressure not shown. 4—4 are small perforations through the wall of this pipe close to the under side of the head. The area and purpose of these perforations will hereinafter appear.

20 25 5—5 are trunnions attached to the cylinder on its diametric line and at the center of gravity, on which the cylinder is carried in the bearings 6 supported by the legs 7. The cylinder thus supported may be inverted by revolving it on the trunnions. The water supply to the valve 8 must be through a flexible connection, as a hose.

30 The cylinder may be held in a vertical position, either upright or inverted, by the engagement of the lugs 9—9 with a lug 10 made fast to the frame.

35 The bottom 11 of the cylinder should be readily detachable and may be revolved by means of the lugs 12 and held in position 40 by a screw thread or by the bayonet catch indicated at 13. To prevent leakage a ring of sheet packing 14—14 may be inserted.

45 In the bottom of the lower head 11 is fixed a pipe nipple 15 through which solution is discharged from the cylinder, and which may communicate with the solution-mixing head through a flexible line, as a hose length with a pipe extension if required.

50 To the lower head is rigidly fixed the plate 16 which may be supported in any convenient manner, as by the studs 17. This plate should conform to the shape of the cylinder, leaving a restricted annular opening 18 the width of which may be from $\frac{1}{16}$ " to $\frac{1}{4}$ " according to the size of the apparatus. In general terms the area of this annular opening may approximate the inside area of pipe 3.

55 The lower end of pipe 3 is brought down close to the plate, leaving a gap 19 between the plate and the carefully squared end of pipe 3. The area of this opening may preferably be approximately one-half the inside cross sectional area of the pipe. The object of this gap is to project a sheet of water

at a relatively high velocity over the plate, which requires that the pipe area be somewhat constricted at the gap 19.

55 A single shell as shown in Figure 1 will produce intermittently one of the solutions required to generate foam. A pair of such shells is required to intermittently produce the two solutions. The operation of the shells is the same for the two solutions, and may be described as for a single shell.

70 The shell being assumed to be empty and water supply shut off at valve 8, it is inverted from the operating position shown in Figure 1, and the bottom 11 (which will then be on top) is removed, leaving the connections 15 attached thereto. The upper head 2 of the shell will now be at the bottom with the water pipe 3 projecting upward therefrom, while the plate 16, being attached to the bottom plate 11, will be out of the way and the cylinder open at the end which is then uppermost.

75 Into the cylinder and around pipe 3 is now poured a sufficient quantity of powdered (a) or (b) chemical to fill it to say 85% of its capacity. The cap 11 is then replaced, the water turned on and the cylinder again inverted, bringing it to its original or operating position. The powder drops to the bottom of the shell in its new position, resting on the plate 16, and the sheet of water passing over this plate rapidly dissolves it away at the bottom, the solution passing downward through the annular opening 18 and underneath the plate 16 into the outlet connection 100 15. Solution proceeds at an even rate until the entire batch of powder is thus dissolved and carried away, this rate increasing or decreasing as the supply of water is increased or decreased. By feeding water at a predetermined rate the production of solution may be controlled as desired.

105 The rate of solution may also be varied by varying the area of the gap 19, as by advancing the lower end of pipe 3 toward or withdrawing it from plate 16 by means of the threaded portion 39, the pipe collar 40 and the union 41. The wider this gap and the lower the velocity of the water sheet issuing therefrom, the slower will be the rate of solution and the more dilute the solution produced. An adjustment may readily be found at which exactly the required amount of water will have passed through the shell at the moment the powder is completely dissolved.

115 The purpose of the perforations indicated at 4 in Figure 1 is to prevent bridging of the powdered material and to force it downward onto plate 16. The pressure inside pipe 3 being necessarily greater than the pressure in the lower portion of the shell (which discharges into a substantially open end) water flowing out of these perforations forms a water piston by which the plug of powder is forced downward as consumed. The area of 125 130

these perforations may be substantially one-seventh of the area of the pipe, but this area is of minor importance as no more water can escape from these holes than is required to fill the shell above the powder, a very small part of the quantity required to bring it into solution. The use of these perforations is optional and they may be omitted if preferred.

The apparatus illustrated in Figures 3 and 10 4 is designed to produce the two solutions simultaneously. By the alternate use of a pair of such units two continuous streams of solution may be produced with a single water inlet and a single outlet for each solution, 15 without the use of any hand operated valves.

As the general construction and functioning of this apparatus are covered by the above description, only the points of difference will be described.

20 Referring to Figures 3 and 4, water under pressure from a source not shown passes through the broken pipe 20 into the branch lines 21 and 22. The two shells of which this unit is composed are identical in construction and operation, and only one side need be described.

Water passing through pipe 21 enters the cap 23 of the trunnion bearing 22, which is cored out to register with a cored hole 24 in the trunnion 25 when the shell 26 is in the operating position shown. These holes do not register when the shell is inverted, and the trunnion and its cap thus form a valve through which water can pass only when the shell is in the upright or operating position.

35 The coring in the trunnion is continued inwardly and communicates with a cored hole 27 extending upwardly through a rib 28 formed in the adjacent side of the shell. This cored hole is carried through the wall of the rib as at 29 and into the opening thus formed is fastened a pipe nipple 30 communicating through an L 31 with a pipe 3 which is identical with the pipe of the same number shown 45 in Figure 1.

On the opposite side of the shell is formed the rib 32 which terminates a short distance above the bottom head 11. Through this rib is cored a passage 33 communicating with 50 a cored hole 34 passing part way through the trunnion 35 and registering with a similar hole 36 formed in the supporting leg 37 and terminating in a screw threaded pipe connection indicated at 38. A solution conductor 55 not shown is to be attached to this connection and it will be noted that the valve formed by the opposed openings in the trunnion and leg is open only when the shell is in operating position and is closed when the shell is inverted for recharging, thus preventing a return flow of solution in case two units have 60 their corresponding discharges connected to a single conductor line. The cored passages 55 and 33 may be replaced by pipes or tubing 65 if preferred.

On inverting the shell and removing the bottom plate 11 for recharging, the shell will be full of water, which must be removed prior to adding the powder. This may be done by tipping the shell to a horizontal position 70 which will allow the water to flow out without bringing the trunnion ports into registry and thereby admitting more water.

While I have described a particular form of apparatus suitable for dissolving a charge 75 of foam producing agent under pressure, it will be obvious that substantially the same results may be obtained by means of modifications of this apparatus entirely within the scope of my invention.

The details shown refer to a preferred construction only, and that which I have invented and wish to claim as broadly as the state of the art will permit is set forth and defined solely in the attached claims.

I claim as my invention:

1. The method of bringing a foam producing agent into solution, which comprises: producing a flow stream of water under pressure; converting said flow stream into a sheet 80 of flowing water under pressure; superposing on said water sheet a body of foam producing agent; forcing said superposed body into continued contact with said water sheet by admitting water under pressure on top of said 85 body; producing a solution of said agent substantially on the plane of contact between said body and said water sheet, and collecting said solution into a flow stream.

2. The method of bringing a foam producing agent into solution, which comprises: producing a flow stream of water under pressure; converting said flow stream into a sheet 90 of flowing water under pressure; superposing on said water sheet a body of comminuted 95 foam producing agent; producing a solution of said agent substantially on the plane of contact between said body and said water sheet, and collecting said solutions into a flow stream.

3. An apparatus for dissolving a foam producing agent comprising, a vessel with vertical cylindrical walls and with one end permanently closed, said vessel being supported on trunnions so as to render it readily reversible 115 end for end; a readily detachable closure for the end opposite the fixed end; a plate attached to said closure, inside said vessel, in a position close to said closure and at a right angle to the vertical axis of said vessel; said 120 plate being of such size as to leave a narrow annular opening between said plate and said cylindrical walls; a pipe for admitting water under pressure into said vessel, said pipe terminating at such distance from said plate 125 as to leave a relatively narrow gap therebetween, said pipe being further provided with a means for the escape of water inside said vessel and close to the fixed end thereof; a means for conducting water into said pipe, 130

and a conductor for discharging solution communicating with the interior of said vessel.

4. An apparatus for simultaneously dissolving two foam producing agents, comprising: a pair of dissolving vessels each substantially as described in claim 3, trunnions of said vessels being so interconnected as to cause the inversion of one of said vessels to simultaneously invert the other of said vessels.

5. An apparatus for dissolving a foam producing agent, comprising: a substantially closed vessel, the lower end of said vessel consisting of a readily detachable closure; a plate horizontally supported in said vessel near the lower end thereof; a passage between said plate and the wall of said vessel; a pipe for admitting water under pressure into said vessel and terminating close to said plate, leaving a narrow space between said plate and the end of said pipe; an opening through the wall of said pipe near the upper end of said vessel; means for conducting water under pressure into said pipe, and means communicating with said vessel at a point substantially below said plate for conducting liquid out of said vessel.

6. An apparatus for simultaneously dissolving two foam producing agents, comprising: a pair of dissolving vessels each substantially as described in claim 5, trunnions for said vessels, said trunnions being so connected as to cause the inversion of one of said vessels to simultaneously invert the other of said vessels.

7. An apparatus for simultaneously producing solutions of two foam producing agents from bodies of solid comminuted agent, comprising: two substantially closed vessels each provided with means for introducing a body of said comminuted solid agent, said vessels being supported by trunnions resting in trunnion bearings, said vessels being so interconnected as to be simultaneously inversible end for end on said trunnions; a passage formed through one trunnion and bearing on each said vessel, said passage communicating at its outer end with a source of supply of water under pressure and at its inner end with means interior to said vessel for converting a flow stream of water into a sheet of flowing water, said sheet being so positioned inside said vessel as to underlie and contact with said body of agent for bringing said agent into solution; and a passage formed through the opposite trunnion and bearing on each vessel, said passage communicating with the interior of said vessel beneath said water sheet and with means exterior to said vessel for separately conducting the solutions produced in the two said vessels to a point of intermixture thereof.

8. An apparatus substantially as defined

in claim 7 in which the passages formed through each bearing and its corresponding trunnion are so located as to be out of register and closed to the passage of liquid when the vessel of which said trunnion is a part is in that position at which the closure is uppermost, and in register and open to the passage of liquid when said vessel is inverted from said position.

9. The continuous method of bringing a foam producing agent into solution which comprises: projecting a flow stream of water against a substantially horizontal surface to convert said flow stream into a substantially horizontal sheet of flowing water, and superposing on said water sheet a body of said agent in comminuted form.

10. An apparatus for continuously dissolving a foam producing agent, comprising: means for producing a sheet of horizontally flowing water; means for retaining a body of the comminuted agent substantially above said water sheet and in contact therewith on a substantially plane surface, and means for withdrawing said water and dissolved agent from below said plane of contact.

In witness that I claim the foregoing I have hereunto subscribed my name this 14th day of September, 1927.
